INTERNAL-COMBUSTION ENGINE

Kenneth R. Maltby, Lavonia Township, Oakland
County, Mich.

Application February 20, 1942, Serial No. 431,655

13 Claims. (Cl. 74—22)

This invention relates to internal combustion engines and, in particular, to engines having reciprocating pistons.

One object of this invention is to provide an internal combustion engine having reciprocating pistons with improved means for transforming the reciprocating motion of the pistons into rotary motion without the use of cranks.

Another object is to provide an internal combustion engine as set forth in the preceding object wherein the reciprocating motion of the piston rod is converted into a rotary motion of the engine shaft by means of a spirally-shaped toothed member meshing with a gear on the engine shaft.

Another object is to provide an internal combustion engine having pistons reciprocable in spiral paths so that the ports by which fuel is admitted and exhaust gases discharged are covered and uncovered during the spirally rotatory motion of the piston as it reciprocates.

Another object is to provide an internal combustion engine as set forth in the object immediately preceding wherein the air or fuel gas is compressed in the space behind the piston and conveyed through a by-pass passageway from the space behind the piston to the space in front of the piston head which constitutes the explosion chamber.

Another object is to provide an internal combustion engine having paired pistons mounted on opposite ends of a common connecting rod and reciprocating as well as rotating in oppositely disposed cylinders, the rotating and reciprocating motion of the piston rod being transformed into rotation of the engine shaft by means of a spiral cam-like member having teeth on the edge thereof, meshing with teeth on a gear on the engine shaft, the lateral surfaces of the cam-like toothed member engaging corresponding mating surfaces on oppositely disposed abutment members through which the piston rod passes.

Another object is to provide an internal combustion engine having pistons rotating as they reciprocate to and fro, the piston head and the cylinder head having shouldered portions which arrive adjacent one another at the top of the stroke so as to provide an explosion chamber whereby reaction of one shoulder against the other as a result of the explosion carries the piston and cam-like member over dead center as they rotate and reciprocate.

Another object is to provide an internal combustion engine as set forth in the preceding objects wherein the pistons have skirts which are

5 cut away at an angle in an axial direction and cooperate with similarly angled elongated ports in the cylinder side walls, these intake and exhaust ports being covered and uncovered by the rotatory reciprocating motion of the piston.

Another object is to provide an internal combustion engine of a modified type (Fig. 10) wherein the pistons reciprocate with the rotation but wherein the reciprocating motion is transformed into a rotatory motion of the engine shaft by a spirally-toothed member mounted loosely on the piston rod and meshing with corresponding teeth in a gear mounted upon the engine shaft.

Another object is to provide an internal combustion engine according to the preceding objects, but of a modified type (Fig. 11), wherein the pistons rotate as they reciprocate and wherein the spirally-shaped member with teeth upon its edges engages fixed abutment rollers in contact with its opposite lateral surfaces as it meshes with the gear mounted upon the engine shaft.

Another object is to provide a combined internal combustion engine and electrical generator (Fig. 12) wherein an elongated cylinder block 25 has cylinders at its opposite ends containing pistons mounted on opposite ends of a common connecting rod which in turn carries a spool-shaped rotor, preferably of permanently magnetic material and moved back and forth between a plu-

30 rality of stator coils which carry electric current generated by this cutting of the lines of force, means engaging the spool-shaped rotor for imparting a rotatory motion thereto in response to the reciprocating motion of the pistons, such 35 as a roller working in a spirally-grooved sleeve encircling the rotor.

Another object is to provide a combined internal combustion engine and electrical generator (Fig. 13) wherein an elongated cylinder block 40 with cylinders at its opposite ends receives a pair of pistons mounted on the opposite ends of a common connecting rod, the connecting rod carrying a spiral cam-like member having teeth on the edge thereof which mesh with an internal gear within a rotor.

Another object is to provide a combined internal combustion engine and electrical generator of a modified type (Fig. 15) with rotating and reciprocating pistons as set forth in the preceding objects but wherein the rotor of permanently magnetic material reciprocates as it rotates within the stator windings, thereby generating an electric current because of the cutting of the lines of magnetic force, the reciprocation and rotation being effected by a spirally-shaped cam member

which engages correspondingly shaped abutment members.

In the drawings:

Figure 12 is a central vertical section through a further modification of the engine shown in Figure 1, wherein there is provided a combined internal combustion engine and electrical generator with a rotating and reciprocating rotor.

Figure 13 is a central vertical section through a modification of the combined internal combustion engine and electrical generator shown in Figure 12, wherein the rotor rotates but does not reciprocate.

Figure 14 is a cross-section along the line 14—14 in Figure 13.

Figure 15 is a central vertical section through further modification of the combined internal combustion engine and generator shown in Figure 12, wherein the rotor also rotates and reciprocates.

General arrangement

In general, the internal combustion engine of this invention consists of a cylinder block containing a pair of opposed cylinder bores having pistons reciprocating therein and interconnected by a common piston rod. The piston rod carries a power transmitting member of a peculiar shape, somewhat like a bent disk arranged at an inclination to the piston rod and having teeth on its edge meshing with corresponding teeth upon a gear mounted on the engine shaft. The power transmitting member is of such a shape (Figs. 1 and 2) that one toothed edge is arranged in a spiral path for 180° of its extent, the other 180° having a reverse spiral path in the opposite direction and returning to the starting point. This power transmitting member at its opposite surfaces engages abutment members with corresponding mating surfaces (Fig. 2 and lower portion of Figure 1) so that the piston rod and the pistons thereon are caused to rotate as they reciprocate. This rotation, however, is always in the same direction, and in a spiral path which returns along a reversed spiral path.

The pistons have skirts which are cut away

5 along curved oblique edges so as to cooperate with obliquely arranged elongated ports in the cylinder walls, covering and uncovering these ports at proper positions during the working cycle. A by-pass conduit or passageway is also provided in each cylinder wall leading to the chamber immediately beneath each cylinder head.

The cylinder head is provided with a shoulder which cooperates with a similar shoulder upon the piston head (Fig. 7) so as to provide a small combustion space when the two shoulders are at their point of nearest approach. The explosion in this space provides an impetus which carries 10 the piston and the power transmitting member over their dead centers. The fuel may be injected directly into the combustion chamber, in which case air is compressed in the space behind the piston head and in the by-pass passageway for discharge into the combustion chamber when the by-pass port is uncovered by the motion of the piston. Optionally, the fuel and air may be previously mixed, as in a carburetor, and fuel gas compressed and delivered in a similar manner to the air previously mentioned.

15 The modification of Figure 10 is similar in some respects to the form shown in Figure 1, except that the pistons do not rotate but merely reciprocate, and hence the ports in the cylinder walls are not elongated to the extent of those in Figure 1. The modification of Figure 11 is likewise similar to the form of Figure 1 except that abutment rollers are provided for engagement by the power transmitting member.

20 The modifications of Figures 12, 13 and 15 employ an internal combustion engine of the general type shown in Figure 1, but also include a rotor of permanently magnetic material cooperating with a wound stator, so that a combined internal combustion engine and electrical generator results. The engine may be either liquid-cooled or air cooled, and such cooling devices have been omitted for simplifying the showing.

Internal combustion engine with rotating and reciprocating pistons

25 Referring to the drawings in detail, Figures 1 to 9 inclusive show a central vertical section through an internal combustion engine according to a preferred embodiment of the present invention. The engine shown in these figures consists of a plurality of left-hand cylinders 20 and right-hand cylinders 21 (Fig. 1) secured as at 22 by means of flanges 23 to a connecting casing 24 (Fig. 4). The cylinders 20 and 21 are similar to one another but have their ports oppositely arranged, so that they are "rights" and "lefts" respectively. Each cylinder 20 and 21 is provided with a cylinder head 25 secured as at 26 to the flange 27 upon the cylinder, and having a portion 28 extending into the cylinder bore 29. The cylinder head portion 28 is provided with an inwardly projecting portion 30 having a lateral cylinder 31 thereon (Fig. 7). Opening into the cylinder bore 29 near the shoulder 30 is a port 32 formed in a boss 33 and serving either for the reception of a fuel injector in the event that liquid fuel injection is employed, or for a spark plug in the event that gaseous fuel is introduced.

30 Each cylinder wall 34 contains an elongated by-pass port 35 (Fig. 2), extending obliquely along the cylinder wall 34, and consisting of an open groove or channel in the cylinder wall 34. Also passing through the cylinder wall 34 and arranged obliquely thereto is an elongated intake

port 36 arranged to admit air or fuel gas into the space behind the piston when it is uncovered by the piston skirt, as explained below. Finally, the cylinder wall 34 contains an elongated exhaust port 37 arranged to be uncovered by the piston head as the piston reciprocates.

Reciprocable in each cylinder bore 29 is a piston 38. For convenience of manufacture the piston 38 is made in two pieces, namely a base portion 39 and a head portion 40 (Fig. 1) having its side portions 41 fitting into an annular groove 42 in the base portion 39. The latter is provided with a bore 43 which receives the one end of the piston rod 44 and is secured thereto as by the pin 45. The pin 45 passes through a transverse bore 46 in the end of the piston rod 44 and likewise through bores 47 and 48 in the base portion 39 and head portion 40 respectively (Fig. 2).

The base portion 39 of the piston 38 is provided with a skirt 49 of irregular shape, it being cut away along the edge of arcuate portions 50 meeting at the point 51 (Fig. 2).

The piston head 40 is provided with a top wall 52 having a top surface 53 (Fig. 1), upper right-hand corner being provided with an inclined surface 54 and a shouldered portion 55 cooperating with the shoulder 31 on the cylinder head portion 30 to provide a combustion space therebetween, as explained above. The relative locations of the ports 35, 36 and 37 and the positions of the piston 38 at various points in its operating cycle are shown in Figure 9.

In order to provide for a combined rotary and reciprocating motion of the pistons 38, the piston rod 44 is provided with a power transmitting member, generally designated 56 (Figs. 1 and 2). This power transmitting member 56 has opposite lateral surfaces 57 and an edge 58 provided with teeth 59. The edge 58 is composed of two parts 60 and 61 respectively (Fig. 2), the one being a reversed replica of the other. The power transmitting member 56 is not a plane body, but resembles a bent disk having its edges 60 and 61 in the form of right and left hand spirals or screws meeting at the locations 62 and 63 respectively. The opposite lateral surfaces 57 of the power transmitting member 56 engage opposed abutment surfaces 64 and 65 formed in abutment members 66 and 67 (Fig. 2) having bores 68 and 69 through which the piston rod 44 loosely passes. The outer portions 70 of the abutment members 66 and 67 are tapered and inserted in retaining sleeves 71 which are provided with flanges 72 (Fig. 2) bolted between the cylinder flanges 23 and the opposite halves 73 and 74 of the casing 24 (Fig. 1). The outer portions of the casing halves 73 and 74, the cylinder flanges 23 and the abutment flanges 72 are bolted together by the bolts 75. The tapered portions 70 of the abutment members 66 and 67 are tapered, and the edges 76 of the retaining sleeve 71 are cut away along an arcuate oblique line in order to avoid the edges of the piston skirts 49.

The abutment surfaces 64 and 65 upon the abutment members 66 and 67 are of shapes matching with the lateral surfaces 57 of the power transmitting member 56, hence are roughly concavely V-shaped to fit the approximately convex V-shape of the surfaces 57 of the power transmitting member 56, these meeting along the edges 62 and 63. Accordingly, the abutment surfaces 64 are fixed in location, and are held in this fixed location by pins 77 (Fig. 1) passing through the retaining members 71 into the abutment members 66 and 67.

The teeth 59 upon the edge 57 of the power transmitting member 56 mesh with similar teeth 78 upon the periphery of a gear 79 which has a central bore 80 receiving the portion 81 of the engine shaft 82 and keyed thereto as at 83 (Fig. 1). The engine shaft 82 is provided with anti-friction bearings 84 on opposite sides of the shaft portion 81, and likewise with an anti-friction bearing 85 for supporting the opposite end of the shaft 82. A tubular shaft housing 86 extends outwardly from the casing half 74 and is closed at its outer end by an annular threaded plug 87 with an oil wiping gasket 88 therein.

Operation

In the operation of the engine shown in Figures 1 to 9 inclusive, the parts follow the two-cycle mode of operation. The fuel may be supplied to the engine either in the form of liquid fuel which is injected into the combustion chamber at the top of the compression stroke so that the heat of compression ignites the fuel as in the Diesel type of engine, or the fuel is mixed with air as in a carburetor and then supplied to the engine. Let it be assumed that the carburetor type of fuel supply is adopted in describing the operation of the engine, and that a spark plug is mounted in the port 32 for injecting liquid fuel at the top of the compression stroke of the piston 38. It will be observed from Figures 1 to 4 that four cylinders 20 and 21 are shown but it will be obvious that multiple banks of cylinders may be employed if desired. As previously stated, the cylinders 20 and 21 and their ports 35, 36 and 37 are similar in construction but oppositely arranged so as to be "rights" and "lefts" of one another.

Let it be assumed that the working parts are in the position shown in Figure 1, and that the upper left-hand piston 38 has completed its compression stroke and arrived at the top of its stroke. The piston 38 has reached this position, not by simple reciprocation, but by rotation combined with reciprocation so that the piston rotates 180° upon its up-stroke and rotates another 180° in the same direction upon its down-stroke. The shoulder 55 upon the top of the piston 38 is so arranged relatively to the shoulder head 25 that it barely clears the latter as it spirals forward upon its up-stroke, and arrives in the position of Figure 7 in the time for fuel ignition.

The position of the piston top 53, skirt edges 50 and ports 35, 36 and 37 are shown in the left-hand portion of Figure 9. The four positions in the cycle shown in Figure 9 may be considered as giving a view of the cylinder bore 29 as it could be laid out on a flat surface, with the vertical plane of the drawing of Figure 1 representing the center line A—A of Figure 9. Thus the line A—A coincides with the intersection of the top of the cylinder bore 29 in Figure 1 with the plane of the paper and the upper and lower lines B—B and C—C coincide with the lower intersection of the cylinder bore 29 with the plane of the paper.

As the piston top 53 reaches its upper extreme limit of motion, the skirt edges 50 uncover the intake port 36 and by-pass port 35 so that fuel gas is admitted to the space behind the piston 38. The piston skirt 49 at this point completely covers the exhaust port 37. The parts are now in the position "Ignition" in Figure 9.

Ignition now takes place in the space between the shoulders 31 and 55, whereupon the reaction therebetween rotates the piston 55 and carries

it past the dead center position indicated by the point 62 of the power transmitting member 56 in Figure 2.

As the piston rod 44 moves backward, it pushes the lateral surfaces 57 of the power transmitting member 56 against the similarly inclined surfaces 64 of the abutment members 66, rotating the edge 58 carrying the teeth 59.

As the power transmitting member 56 rotates, the meshing of its teeth with the teeth 78 upon the gear 79 causes the latter to rotate, and with it the engine shaft 82. Meanwhile, the lower right-hand piston 38 shown in Figure 1 is performing the same operation and at the same stage in the cycle as the upper left-hand piston under consideration. The upper right-hand piston and the lower left-hand piston, however, are at the opposite ends of their cycle, namely at the point where the burnt gases are being discharged through the exhaust ports 37. As the upper left-hand piston 38 moves backward to the right after ignition and explosion have taken place, its skirt edge 59 covers up the intake port 36 compressing the gas in the space behind the piston 38 and into by-pass channel 35.

The expansion stroke now takes place. The burning gases above the top of the cylinder head 40 expand and push the piston 38 backward until its top 53 starts to uncover the exhaust port 37, as shown in the portion of Figure 9 marked "Exhaust." Meanwhile, the skirt 49 has covered up the intake port 36 as the piston 38 has rotated while it has moved backward, but the bypass channel 35 remains uncovered. As a consequence, the fuel charge behind the piston 38 is compressed in the bypass channel 35 which, it will be remember, is in the form of a spiral channel in the cylinder wall 34. The piston top 53 is now nearing the bottom of its stroke.

The exhaust portion of the cycle now takes place as the piston top 53 completely uncovers the upper edge of the exhaust port 37, so that the burning gases rush out through this port and are discharged into a suitable muffler or into the atmosphere, as the circumstances dictate. At the same time, however, the piston top 53 has receded to the point where it uncovers the upper end of the bypass or channel port 35. This permits the fuel gases compressed in the bypass port 35 to rush into the combustion chamber, assisting in the scavenging of the combustion chamber by aiding in driving out the burnt gases. The parts are now in the positions indicated by the portion of Figure 9 marked "Exhaust" and the piston 38 has reached the bottom of its stroke. By changing the angles of the forward edge of the exhaust port 37 and the inclined piston head portion 54, the relationship of the opening of the exhaust port 37 relatively to the bypass port 35 may be altered and accordingly the scavenging action varied as desired. This permits the exhaust port 37 to be opened first on the expansion stroke but allows the exhaust port 37 and the bypass port 35 to be closed simultaneously. Thus the exhaust port 37 and by-pass port 35 may be opened or closed simultaneously during the stroke in one direction but opened or closed separately during the stroke in the opposite direction or both may be opened separately in both directions. In the example described, the exhaust port 37 is preferably opened before the bypass port 35 on the reverse or expansion stroke but are simultaneously closed on the forward or compression stroke.

With the fuel gas charge admitted to the com-

bustion chamber, the piston 38 continues its rotation and starts upon its forward stroke. The skirt edge 59 now uncovers the intake port 36 but covers the exhaust port 37 and by-pass port

5 25. The parts now occupy the positions shown in the portion of Figure 9 marked "Compression." The suction created behind the advancing piston 38 draws in fuel gas through the intake port 36 into the space behind the piston 38 as 10 the top 53 of the piston moves toward the top of the cylinder head 25, compressing the fuel charge.

As the piston 38 reaches its point of nearest approach to the cylinder head 25, the charge is compressed. The piston head shoulder 55 moves 15 upward beneath and past the corresponding shoulder 31 upon the cylinder head 25, reaching the position shown in Figure 7. Meanwhile, the piston skirt edge 59 has uncovered the intake port 36 and the entire bypass port 35. The parts 20 are now in the positions shown in the left-hand portion of Figure 9 marked "Ignition." Ignition of the charge between the shoulders 31 and 55 then takes place and the foregoing cycle is repeated.

25 While this is occurring, the lateral surfaces 57 of the power transmitting member 56 have first engaged the abutment surface 64 of the abutment member 66 on the forward stroke and thereafter engaged the abutment surface 65 of the abutment member 67 on the rearward stroke of the upper left-hand piston 38. Thus, the power transmitting member 56 rotates continuously in one direction as it reciprocates, the teeth on one half its edge contacting the teeth 78 of the gear 79 on the forward stroke and those of the other half contacting the teeth 78 on the return stroke. By this means, the spirally-shaped power transmitting member 56 converts the rotating and reciprocating motion of the pistons 38 into a pure 30 rotation of the gear 79 and engine shaft 82. Moreover, the mass of the rotating pistons 38 and power transmitting member 56 provides a flywheel effect because of the momentum of these parts. This flywheel effect also assists in carrying the power transmitting member 56 over its dead center points 62 and 63.

Figure 11 modification

The modification shown in Figure 11 is similar in construction to that shown in Figures 1 to 9 inclusive, and similar parts are similarly designated. The power transmitting member 56 in Figure 11 is similar in principle to the power transmitting member in Figures 1 to 9 inclusive, but the abutment members 67 are omitted and the faces 57 are altered somewhat to compensate for the fact that the rollers 95 have definite diameters. The retaining members 71 of Figure 2 are replaced by closure members 90 having flanges 91 interposed between the cylinder flanges 23 and the casing 92 to which the cylinders 20 and 21 are directly bolted, as at 93.

In place of the abutment members 66 and 67, the modification of Figure 11 provides abutment rollers 94 and 95 supported upon studs 96 threaded into sockets 97 in projections 98 comprising bosses extending inwardly toward the piston rod 44.

The operation of the modification of Figure 11 70 is substantially the same as that of Figures 1 to 9 inclusive. The thrusts of the side surfaces 57 of the power transmitting member 56 are taken by the abutment rollers 94 and 95 instead of by the abutment surfaces 64 and 65, the one acting on the forward stroke of the upper left-hand

piston and the other on the rearward stroke thereof. The reversal of the pistons 38 may be made less abrupt than in Figs. 1 to 9 inclusive as the turning points corresponding to 62 and 63 may be rounded off as desired. The acceleration or deceleration of the reciprocation of the pistons 38 can be varied by varying the configuration of the faces 57.

Figure 10 in modification

The Figure 10 modification differs essentially from that of Figures 1 to 9 inclusive in having non-rotation pistons, hence employing straight ports. The power transmitting member accordingly rotates loosely upon the piston rod.

In particular, the modification of Figure 10 includes cylinders 100 and 101 having heads 102 bolted thereto as at 103 and bores 104 containing intake ports 105, exhaust ports 106 and by-pass ports 107 and 108 interconnected by a by-pass passageway 109. Pistons 110 connected as at 111 to the piston rod 112 are reciprocably but non-rotatably mounted in the cylinder bores 104. The piston rod 112 passes through bores 113 and abutment members 114 and 115 held within the retaining members 116 and 117 having flanges 118 clamped between the cylinder flanges 119 and the casing halves 120 and 121 as by the bolts 122. The abutment members 114 and 115 are provided with opposed abutment surfaces 123 and 124 (Fig. 10) of a similar configuration to the abutment surfaces 64 and 65 of Figure 2, and engaging the lateral surfaces 125 and 126 of the power transmitting member 127 in a similar way. The power transmitting member 127 is provided with a hub 128 and a bore 129 therein loosely surrounding the piston rod 12 and held in position by retaining collars 130 pinned thereto as at 131. The teeth 132 of the power transmitting member 127 mesh with teeth 133 upon the gear 134 which is mounted upon the engine power output shaft (not shown) similar to the arrangement shown in Figure 1.

The cylinder walls 135 are provided with ports 136 for the reception of a spark plug or other ignition means. The piston 110 is provided with a baffle plate 137 projecting upwardly from the top 138 thereof, and is also provided with a skirt 139 which covers and uncovers the ports 106 and 107. A spring pressed poppet valve 140 is mounted in a plug 141 threaded into the port 105 and has a stem 142 with a spring 143 engaging the plug 141 at one end and an abutment washer 144 at its other end, thereby urging the poppet valve 140 upwardly into closing engagement with a valve seat 145 in the threaded plug 141. Passages 146 open through the threaded plug 141 into an intake conduit 147.

In the operation of the modification shown in Figure 10, the pistons 110 follow the usual two-cycle mode of operation. As the upper left-hand piston moves to the left upon the compression stroke, it draws in fuel gas through the intake port 105, in which the poppet valve 140 opens under the suction thus created. Meanwhile, the charge has been exploded in the combustion chamber in the upper right-hand corner of Figure 10 and the right-hand piston 110 moves downwardly until it uncovers the exhaust port 106 and the upper by-pass port 107. The fuel charge which has been compressed beneath the upper right-hand piston 110 rushes through the lower by-pass port 108, the by-pass conduit 109 and the upper by-pass port 107 into the combustion

chamber, past the baffle 137 while the burnt gases escape through the exhaust port 106.

The compressed charge in the left-hand cylinder is now ignited and the left-hand piston moves inwardly, compressing the charge in the space behind the left-hand piston 110 and also in the by-pass passageway 109 while the charge in the right-hand combustion chamber is being compressed as the right-hand piston 110 moves outward. In this way, the piston rod 112 reciprocates to and fro. The pistons 110, however, do not rotate since the power transmitting member 127 is free to rotate upon the piston rod 112 against the thrust collars 130. The rotation of the power transmitting member 127 as it reciprocates causes the gear 134 to rotate, thereby rotating the shaft 82. The thrust surfaces 123 and 124 alternately bear the engagement of the corresponding thrust surfaces 125 and 126 on the power transmitting members 127 as the engine operates. The principles of operation of the power transmitting member 127 are thus broadly similar to those of the power transmitting member 56 of Figures 1 to 9 inclusive.

Combined engine and electrical generator

The three modifications shown in Figures 12 to 15 inclusive include rotating and reciprocating pistons substantially similar to those shown in Figures 1 to 9 inclusive and are similarly designated. In each case, however, the power is transmitted to a rotor, preferably of permanently magnetic material, which rotates, and in some instances also reciprocates within a stator having windings. In this manner, an electrical current is generated as the lines of force of the rotor cut the windings of the stator.

The modification shown in Figure 12 employs a spool-like rotor 140 with an annular channel 141 containing a sleeve 142 of non-magnetic material containing a groove 143 arranged in a spiral direction. The rotor 140 is preferably of permanently magnetic material. This groove 143 is similar in configuration to the edge of the power transmitting member 56 of Figures 1 to 9 inclusive. In other words, the groove 143 spirals up in an oblique direction on one side of the spool 140 and spirals backward to its starting point on the other side thereof. An abutment roller 144 mounted on a stud 145 threaded into a socket 146 in a projection 147 of the casing 148 engages the groove 143. The casing 148 contains a pair of annular spaced windings or coils 149 and 150 wound on insulated drums 151 and 152 and spaced apart from each other axially along the piston rod 44.

In the operation of the engine of Figure 12, the cycle of operation follows that already described in connection with Figures 1 to 9 inclusive, and the various ports are covered and uncovered in a similar manner producing a similar cycle of operation. Closure members 153 and 154 are bolted into place as at 155 and have bores 156 for the passage of the piston rod 42. The casing 148 is bolted into position as at 149a against the opposite cylinder flanges 23.

In the operation of the modification shown in Figure 12, the pistons 38 reciprocate to and fro in the manner already described in connection with Figures 1 to 9 inclusive and the same cycle of operations is carried out. The rotor 140 and non-magnetic sleeve 142 are secured to each other and to the piston rod 44 in any suitable manner, such as by the pin 157, so that these parts rotate and reciprocate as a unit.

As the piston rod 44 moves to and fro during the operation of the engine portion of the machine, the rotor 140 moves to and fro into and out of the stator windings 149 and 150. As the magnetic lines of force from the rotor 140 cut the windings 149 and 150, an alternating electric current is induced therein. This electrical current may be withdrawn for consumption in any suitable manner. The reciprocation of the engine may be varied so as to vary the frequency of alternation of the current.

The modification shown in Figures 13 and 14 is still more similar to the form of the engine shown in Figures 1 to 9 inclusive, especially as regards the construction of the engine portion of the machine. Similar parts are therefore correspondingly designated. The teeth 59 upon the power transmitting member 57 of the Figure 13 modification, however, engage internal gear teeth 160 upon the hub of a rotor 161 which is rotatably supported upon anti-friction bearings 162 mounted in the spiders 163 bolted as at 164 to the engine cylinder flanges 23. The outer portions of the spiders 163 are bolted as at 165 to an annular stator 166 which is provided with multiple axial recesses or grooves 167 adapted to receive windings 168. The rotor 161 is preferably of permanently magnetic material and is provided with pole portions 169 projecting outwardly from the periphery thereof (Fig. 14). The rotor 161 is not reciprocable but solely rotatable.

In the operation of the modification of Figure 13, the engine portion operates in a substantially similar way to the engine of Figures 1 to 9 inclusive. As the piston rod 44 and the power transmitting member 57 reciprocate and rotate to and fro, the motion thereof is transmitted through the internal gear teeth 160 to rotate the rotor 161. As the latter is of permanently magnetic material, its lines of force cut the windings 168 and induce an alternating electrical current in these windings. This alternating current may likewise be drawn off and consumed in any desirable manner and the frequency of alternation can likewise be regulated by regulating the speed of the engine portion.

The modification shown in Figure 15 likewise has an engine portion similar to that shown in Figure 13, and this is only in the mode of transmitting the power and of causing the reciprocation. For this purpose the power transmitting member 56 is replaced by a power transmitting cam 170 mounted upon the piston rod 44 and having opposite surfaces 171 engaging the abutment surfaces 64 and 65 of abutment 66 and 67 similar to those of Figure 1. Secured to the periphery 172 of the power transmitting member 170 is the hub 173 of a rotor 174 of permanently magnetic material. The latter is provided with poles 175 projecting outwardly from the periphery thereof in a manner similar to the rotor 161 of Figure 14, these poles passing within windings 176 within recesses 177 in an annular stator 178 bolted as at 179 to the spider 180 in a manner similar to Figure 14.

The operation of the modification of Figure 15 is broadly similar to that of Figures 12 to 14 inclusive. The rotor 174, however, reciprocates to and fro with the piston rod 44 as the engine portion of the machine follows the same operating cycle as the engine of Figures 1 to 9 inclusive. The rotor 174 thus rotates as it reciprocates to and fro within the windings 176 cutting them with its magnetic lines of force and inducing an alternating current within these windings. This

alternating current, as before, may be taken off and consumed in any conventional manner and the frequency thereof may be varied by varying the speed of the motor.

5 As previously stated in connection with the operation of the form shown in Figures 1 to 9 inclusive, the mass of the pistons and the other rotating parts mounted on the piston rod creates momentum in rotation which produces a flywheel effect. This flywheel effect assists in carrying the machine over its dead center positions, such as those corresponding to the points 62 and 63 of the power transmitting member 56 (Fig. 2). Moreover, the rotors of the electrical generator associated with the engine in the modifications of Figures 12 to 15 inclusive add to this momentum and increase this flywheel effect.

10 While a specific embodiment of the invention has been described and illustrated, it will be understood that various modifications may be made within the scope of the appended claims without departing from the spirit of the invention.

15 It will be further observed that in the opposed piston type of engine described herein, the compression strains are borne by the piston rod 44 and not by the bearings as in the conventional type of engine with crankshaft. Consequently the bearings of the present engine, being free from such strains, have much longer life. The 20 only loads taken through the bearings are the loads imposed by the power transmitting member 56 on the gear 79.

25 What I claim is:

1. In an internal combustion engine, a cylinder, a piston reciprocable in said cylinder, a piston rod connected to said piston, a power output member, spirally-shaped power transmitting means operatively connecting said piston rod with said output member and a housing encircling said spirally shaped power transmitting means having guide means engaging said spirally shaped power transmitting member for imparting rotary motion to said output member.

30 2. In an internal combustion engine, a cylinder, a piston reciprocable in said cylinder, a piston rod connected to said piston, a power output member, and spirally-shaped means for effecting simultaneous reciprocation and rotation of said piston said cylinder and piston being provided with complementary projections to initiate rotation of said piston at one end of its stroke.

35 3. In an internal combustion engine, a cylinder, a piston reciprocable in said cylinder, a piston rod connected to said piston, a power output member, a guide housing encircling said rod and spirally-shaped means on said piston rod engaging within said guide housing for controlling reciprocation of said piston and converting said reciprocation to rotary motion.

40 4. In an internal combustion engine, a cylinder, a piston reciprocable in said cylinder, a piston rod connected to said piston, a power output member, and spirally shaped toothed mechanism on said piston rod and operatively connecting said piston rod with said output member.

45 5. In an internal combustion engine, a cylinder, a piston reciprocable and rotatable in said cylinder, a piston rod connected to said piston, a rotary power output member, a spiral guide housing and means connected to said piston rod within said housing and engaging said power output member for converting the reciprocation and rotation of said piston rod into rotation only of said power output member.

50 6. In an internal combustion engine, a cylinder,

der, a piston reciprocable and rotatable in said cylinder, a piston rod connected to said piston, a rotary power output member, a spirally shaped toothed member connected to said piston rod and meshing with said toothed output member for converting the reciprocation and rotation of said piston rod into rotation only of said toothed element and output member and a guide member engaging the spirally shaped toothed member for guiding the same in a spiral path during each stroke of the piston.

7. In an internal combustion engine, a cylinder, a piston reciprocable and rotatable in said cylinder, a piston rod connected to said piston, a rotary power output member, a spirally-shaped power transmitting member connected to said piston rod, a housing encircling said power transmitting member and means within said housing engaging said power transmitting member for spirally guiding said power transmitting member and converting the reciprocation and rotation of said piston rod into rotation only of said power output member.

8. In an internal combustion engine, a cylinder, a piston reciprocable and rotatable in said cylinder, a piston rod connected to said piston, a rotary power output member having a toothed element thereon, and means including a spirally-shaped toothed power transmitting member meshing with said toothed element for converting the reciprocation and rotation of said piston rod into rotation only of said power output member said piston and cylinder having complementary projecting portions to initiate rotation of said spirally toothed element.

9. In an internal combustion engine, a cylinder, a piston reciprocable and rotatable in said cylinder, a piston rod connected to said piston, a rotary power output member having a toothed element thereon, a spirally-shaped toothed power transmitting member meshing with said toothed element, and means engaging said power transmitting member for converting the reciprocation

and rotation of said piston into rotation only of said power output member.

10. In an internal combustion engine, a cylinder, a piston reciprocable and rotatable in said cylinder, a piston rod connected to said piston, a rotary power output member, a bent cam-like member connected to said piston rod and having opposed edges of opposite spiral configurations, and means engaging said cam-like member for converting the reciprocation and rotation of said cam-like member and piston rod into rotation only of said power output member.

11. In an internal combustion engine, a cylinder, a piston reciprocable and rotatable in said cylinder, a piston rod connected to said piston, a rotary power output member, a bent cam-like member connected to said piston rod and having opposed toothed edges of opposite spiral configurations, abutment means engaging said cam-like member, and a toothed element on said power output member meshing with said toothed edges of said cam-like member.

12. In an internal combustion engine, a cylinder, a piston reciprocable in said cylinder, a piston rod connected to said piston, a rotary power output member, a toothed element connected to said power output member, a bent cam-like member loosely rotatably mounted on said piston rod and having opposed toothed edges of opposite spiral configurations meshing with said toothed element, and abutment means engaging said cam-like member.

13. In an internal combustion engine, a cylinder, a piston reciprocable in said cylinder, a piston rod connected to said piston, a rotary power output member, a toothed element connected to said power output member, a bent cam-like member loosely rotatably mounted on said piston rod and having opposed toothed edges of opposite spiral configurations meshing with said toothed element, and abutment rollers engaging said cam-like member.

KENNETH R. MALTBY.
